TRACK SWITCH STAND

James E. Trosper, Danville, Ill.

Application February 28, 1947, Serial No. 731,443

3 Claims. (Cl. 246—393)

1

My present invention, in its broad aspect, has to do with improvements in safety switch operating and latching devices, and more particularly it is my purpose to provide a switch operating mechanism which in one position is actuated from the side of the tracks and out of the way of rolling stock thereon so that the operator is in no danger of being injured. My device is especially adapted for use in mines and the like, where it has heretofore been the practice to take a position in the middle of the track and kick over the switch latch with the feet to permit the empty car to enter the working place where it is to be loaded. In practice, a motor pushes a string of cars in front of it and cars are cut-off and pushed into the spur or switch whereupon a trip rider, who carries a hook pulls the switch back by stepping down and reaching in front of the next car and pulling the latch back to strengthen the main track. With my present invention, the operator stands at the side of the track, out of the way of danger, and operates the switch. To throw the switch over to open the spur it is merely necessary to step on the center actuating bar of the switch, and to bring the switch back, it is merely necessary to step on a pedal at the side of the track and out of the way of danger.

My latch is simple in construction and positive in operation, and the switch operating mechanism is sturdy, practical and efficient and has no parts which are likely to get out of order or become deranged or inapt for use.

Other and equally important objects and advantages of my invention will be apparent from the following description and drawings, but it is pointed out that changes in form, size, shape, construction and arrangement of parts is permissible within the purview of my broad inventive concept and within the scope of the appended claims.

In the drawings wherein I have illustrated a preferred form of my invention:

Figure 1 is a plan view of a main line, spur and switch equipped with my invention, with the switch shown in open position;

Figure 2 is a longitudinal section through my switch operating mechanism and latch in its open position and although the actuating elements are shown in a straight line it will be understood that there is sufficient play in the joints to permit the pin at the center to move downwardly slightly below a plane extended through the pivot points at the ends;

2

Figure 3 is a longitudinal section of the same in closed position after the latch has been tripped;

Figure 4 is a perspective view of the tongue of the switch operating bar;

Figure 5 is a perspective view of the forward U-shaped slide;

Figure 6 is a perspective view of the rear U-shaped slide;

Figure 7 is a perspective view of the switch operating rod connected with the tongue;

Figure 8 is a side view of the switch pull bar;

Figure 9 is a plan view of a modified form of the switch actuating structure per se with the latch removed, and

15 Figure 10 is a section on the line 10—10 of Figure 9.

In the drawings wherein like characters of reference are used to designate like or similar parts:

20 The numeral 1 designates the main line tracks, 2 a spur line, 3 the switch from the main line to the spur line and back, and 4 the ties. Two of the ties 5 and 6 are extended, as shown in Figure 1, to form supports for my switch operating device and latch. Mounted on the triangular brackets 7, attached as at 8, respectively to the ties 5 and 6, is an anchoring pin 9. Connected centrally of the pin 9 is a pull spring 10, the other end of which is connected to the upstanding ear 11 of a pull rod 12. The pull rod 12 is flat and turned, as at 13, at its end—as shown in Figure 8—to engage a bolt 14 connecting the rod with the switch operating bar 15. The normal pull of the spring 10 is to close the switch to the main line.

25 Also attached to the bolt 14 is a tongue 16 having a bifurcated end 17 formed with opposed eyes 18, through which is received the T-head 19 of a latch rod 20, which has a threaded end 21—see Figure 7. Slidably mounted by means of a slot 22 on the tongue 16 is a U-shaped forward latch member 23—see Figure 5—and slidably mounted by opening 24 on the rod 20 is a rear U-shaped latch member 25—see Figure 6. A nut

30 26 on the threaded end 21 of the rod 20 functions as a stop to prevent disengagement of the member 25 from the rod. A push spring 27 is mounted about the rod 20 and bears against the eyes 18 and T-head 19 of the rod 20, at one end and against the U-shaped member 25 at the other.

35 Pivoted on the pin 9 is a latch arm 28 having side members or bars 29 and angled upwardly, as at 29a, at its rear end adjacent the cross strap 30 to provide a foot pedal. To the ends of the side members is mounted a transverse pin 31 to

which are pivotally mounted the side members or bars 32 of another latch element 33, which side members are pivotally engaged by the side arm 34 of the forward U-shaped member 23. The side arms 35 of the rear U-shaped member 25 are pivoted to the side members 32 of the latch element 33 between their ends.

In operation, assuming that the switch is open to the spur, as in Figures 1 and 2, with the latch members 28 and 33, are horizontally aligned with the angled part 29^a extending up, as in Figure 10, to present the foot pedal cross bar 30, as shown, the car having been cut into the spur, it is merely necessary to step on the bar 30 to pivot the members 28 and 33 to the position shown in Figure 3, whereupon the action of springs 19 and 27 is to pull and push the switch operating rod 15 to throw the switch 3 to close the spur and open the main lines. To return the switch to its original position, as shown in Figure 1, it is merely necessary to step on the pin 31 to press down the members 28 and 33 to the positions of Figures 1 and 2 to again throw the switch to open the line to the spur.

It will be understood that although the pin 31 is illustrated with the center thereof in a plane extended through the bolt head 19 and pin 9 the play in the bolt holes through which the pin 31 extends is sufficient to permit the pin 31 to be forced downwardly below a plane extended through the center of the head 19 and pin 9 whereby the elements are locked in the position shown in Figure 2 with the latch in the open position.

In Figures 9 and 10 a modified form of the invention is shown wherein the rod 29 and its component elements are removed and the side members 32 are connected directly to the tongue 16 by the bolt 49. This form of the invention being used when a spring switch is not involved.

From the foregoing it is believed that the operation and advantages of my invention will be apparent, but it is again emphasized that interpretation of its scope should only be conclusive when made in the light of the subjoined claims.

I claim:

1. In a switch actuator for a track having rails mounted on ties, the combination which comprises an anchoring pin positioned at one side of the track and spaced from the rails thereof, means mounting the anchoring pin on the ties of the track, a pair of bars pivotally mounted on the said pin and extended toward the track, a coacting pair of bars pivotally connected to the bars extended from the anchoring pin, a tongue to which the said coacting pair of bars is attached, a latch member pivotally mounted on the track ends of the said coacting pair of bars and through which said tongue extends, means connecting the tongue to movable switch elements of the track, a spring positioned between the said coacting bars for placing compression on the tongue to retain the switch in the open position, and a spring connected across the outer ends of both pairs of bars for placing compression in the bars with the said pairs of bars in horizontal align-

ment and for urging the said bars to retracted positions.

2. In a switch actuator for a track having rails mounted on ties, the combination which comprises an anchoring pin positioned at one side of the track and spaced from the rails thereof, means mounting the anchoring pin on the ties of the track, a pair of bars pivotally mounted on the said pin and extended toward the track, said bars having upwardly disposed ends extended beyond the said anchoring pin providing a foot treadle for urging the opposite ends of the bars upwardly, a coacting pair of bars pivotally connected to the bars extended from the anchoring pin, a tongue to which the said coacting pair of bars is attached, a latch member pivotally mounted on the track ends of the said coacting pair of bars and through which said tongue extends, means connecting the tongue to movable switch elements of the track, a spring positioned between the said coacting bars for placing compression on the tongue to retain the switch in the open position, and a spring connected across the outer ends of both pairs of bars for placing compression in the bars with the said pairs of bars in horizontal alignment and for urging the said bars to retracted positions.

3. In a switch actuator for a track having rails mounted on ties, the combination which comprises an anchoring pin positioned at one side of the track and spaced from the rails thereof, means mounting the anchoring pin on the ties of the track, a pair of bars pivotally mounted on the said pin and extended toward the track, said bars having upwardly disposed ends extended beyond the said anchoring pin providing a foot treadle for urging the opposite ends of the bars upwardly, a coacting pair of bars pivotally connected to the bars extended from the anchoring pin, a tongue to which the said coacting pair of bars is attached, a latch member pivotally mounted on the track ends of the said coacting pair of bars and through which said tongue extends, means connecting the tongue to movable switch elements of the track, a spring positioned between the said coacting bars for placing compression in the bars with the said pairs of bars in horizontal alignment, a spring positioned between the bars with one end connected to the anchoring pin, a lever connecting the opposite end of the spring to the said tongue and a compression spring positioned between the said coacting bars and connected to the inner end of the tongue for urging the tongue outwardly from the bars.

JAMES E. TROSPER.
